A. B. MARSTON.

BUCKET.

APPLICATION FILED FEB. 11, 1908.

918,686.

Patented Apr. 20, 1909.

UNITED STATES PATENT OFFICE.

ARCHIBALD B. MARSTON, OF NEW ORLEANS, LOUISIANA.

BUCKET.

No. 918,686.

Specification of Letters Patent.

Patented April 20, 1909.

Application filed February 11, 1908. Serial No. 415,431.

To all whom it may concern:

Be it known that I, ARCHIBALD B. MARSTON, a citizen of the United States, residing at New Orleans, in the parish of Orleans and State of Louisiana, have invented certain new and useful Improvements in Buckets, of which the following is a specification, reference being had to the accompanying drawings.

10 My invention relates to improvements in buckets and particularly to improvements in what are known as dip buckets, which are used in the gathering of crude sap from pine trees in the turpentine regions of this country.

15 An object of my invention is to provide a bucket of the class just described which will be strong and durable in construction and which will afford ready and efficient means for removing the gum from the dip paddle 20 used to remove the crude sap or gum from the cavity of the tree, such cavity being commonly called the "box".

In the drawings illustrating the principle 25 of my invention and the best mode now known to me of applying that principle, Figures 1 and 2 are sectional views showing so much of my new dip bucket as is necessary to illustrate my invention; Figs. 3 and 4 are 30 sectional views of another form of my new bucket; and Fig. 5 is a detail showing in elevation the dip paddle.

In Figs. 1 and 2 there is shown one form of 35 the mechanism for cleaning the gum from the blade *c*. As shown in Fig. 2, the bar *e* is at each end riveted to the wall *a* of the bucket and is slightly inclined to the vertical; and coöperating with this bar *e* is a wiper *f* rotatably mounted in the sides of the bucket, as at *g*, and provided with a handle 40 *h*. The wiper *f* normally rests against the stop-lug *i*, as is indicated by the dotted lines in Fig. 2. When it is desired to clean the paddle of the gum collected upon it, the blade *c* is thrust down between the wiper *f* 45 and the bar *e* and the wiper is then thrust forward against the blade *c*, which is thus held firmly between the bar *e* and the wiper *f*. The blade *c* is then withdrawn; and the spaces left between the bar *e* and the blade *c* 50 and between the latter and the wiper *f* allow the gum to fall freely from the blade, as the latter is withdrawn. In this form both sides of the blade *c* are cleaned at a single stroke.

The same result is obtained by means of 55 the structure shown in Figs. 3 and 4, the latter being a sectional view on the line A—A of Fig. 3. In this form the bar *j* doubles back upon itself for a portion of its length and its free end is slightly curved, as is shown 60 at *k*. The interval *m* between the curved end *k* and the opposed side *n* of the bucket permits the blade *c* to be readily passed between the two parts of the bar *j*. Then by 65 slightly tipping the paddle, the two faces are made to contact with the bar, one face against each portion of the bar, as is shown in Fig. 4. The interval *m* and the distance *o* between the parts of the bar *j* may be varied 70 without departing from the spirit of my invention.

It is to be observed that the bar *e* is firmly fastened against movement and sustains the downward pressure of the paddle blade and serves to wipe the lower face thereof, while 75 the upper face is cleaned by the wiper *f*.

In the form shown in Figs. 3 and 4, the short bar *e* wipes the upper face of the paddle blade, while the long bar, which has both its ends firmly fastened against movement in 80 the wall of the bucket, sustains the downward pressure of the paddle blade and serves to clean the lower face thereof. The interval *m* and the distance between the bars permit the insertion, tipping and withdrawal of the 85 paddle blade.

I claim:

1. A bucket provided with a bar extending from side to side thereof and fastened firmly against movement at each end to the wall of 90 the bucket; and a second bar which extends substantially parallel to the first named bar and has one of its ends secured to the wall of the bucket; the first named bar serving to sustain the pressure of the paddle blade and 95 to clean the lower face of the same, and the other bar serving to clean the upper face of the paddle blade; the distance between said bars permitting the insertion, tipping and withdrawal of the paddle blade. 100

2. A bucket provided with a bar extending from side to side thereof and fastened at each end firmly against movement to the wall of the bucket; and a second bar having its ends pivotally mounted in the wall of the 105 bucket and extending substantially parallel to the first-named bar; the latter serving to sustain the pressure of the paddle blade and

to clean the lower face of the same, while the other bar serves to clean the upper face of the paddle blade; the distance between said bars permitting the ready insertion and withdrawal of the paddle blade.

In witness whereof I hereunto set my hand in the presence of the two undersigned wit-

nesses at said New Orleans, this the 6th, day of February, 1908.

ARCHIBALD B. MARSTON.

Witnesses:

EDWARD PIERSON,
CLIFFORD G. HAYS.
